FIG. 4.

Patented June 22, 1926.

UNITED STATES PATENT OFFICE.

WILLIAM F. HIATT, OF INDIANAPOLIS, INDIANA.

TOOL FOR REMOVING AND REPLACING PISTON RINGS.

Application filed March 6, 1925. Serial No. 13,476.

This invention relates to an improved tool for applying or removing piston rings, being especially, although not exclusively, designed for use in connection with the piston rings of internal combustion engines, and seeks, among other objects, to provide a tool by the use of which a piston ring may be easily and quickly applied and as easily removed, without likelihood of injury to the ring or injury to the walls of the ring groove of the piston.

The invention seeks, as a further object, to provide a tool which may be operated to expand the ring so that the ring may be applied or removed over the piston, and wherein means will be provided for firmly retaining the ring upon the tool so that the ring cannot spring free out of control.

A further object of the invention is to provide a tool wherein the retaining jaws employed will, as the ring is expanded, be automatically pressed into engagement with the end portions of the ring, and wherein the spring pressure on said jaws will be increased with the increase in the expansion of the ring so that the ring will at all times be firmly held upon the tool.

And the invention seeks, as a still further object, to provide a tool of simple construction without sacrificing the efficiency of the tool.

Other and incidental objects will appear hereinafter.

In the accompanying drawings:

Figure 1 is a side elevation of my improved tool.

Figure 2 is a view showing the tool engaged with a conventional piston ring, the ring being illustrated in dotted lines.

Figure 3 is an end elevation of the tool.

Figure 4 is a detail sectional view on the line 4-4 of Figure 1, looking in the direction indicated by the arrows.

In carrying the invention into effect, I employ a pair of coacting levers 10. These levers are flat and are pivotally connected as at 11. The rear end portions of the levers are curved away from each other to provide handles while the forward end portions of the levers are straight and form a pair of prongs 12 terminating in tips 13. These tips are provided with straight inner edges and curved outer edges so that when brought together into mating relation, as shown in Figure 1, the tips form a wedge-shaped entering terminal. Projecting from

the levers at the plane of the pivot 11, are oppositely directed lateral arms 14 and formed on the prongs 12 at the base ends of the tips 13 are oppositely directed lateral ears 15. Swingingly mounted upon the ears 15 is a pair of U-shaped ring retaining jaws 16, the sides of which straddle said ears to receive rivets 17 pivotally mounting the jaws, and projecting from the sides of each jaw is a pair of longitudinally extending side flanges 18 shaped to embrace a piston ring. The outer ends of the arms 14 are given a half turn and slidably through the turned ends of the arms are connecting rods 19. At their forward ends these rods are provided with flat heads 20 which are freely received between the sides of the jaws 16 and are pivotally connected therewith by rivets or like fastening devices 21 while at their rear ends, the rods are, as shown in Figure 4, turned laterally to form overhanging lugs 22 to coact with the arms 14 for limiting the jaws in their forward swinging movement relative to the prongs 12. Surrounding the rods to bear between the heads 20 and the ends of the arms 14 are springs 23 pressing the jaws 16 forwardly.

Assuming now that it is desired to remove a ring from a piston, the handles of the levers 10 are swung apart to the position shown in Figure 1, when the wedge-shaped terminal formed by the tips 13 is inserted in the ring groove and forced between the ends of the ring. The ring will thus be expanded slightly so that the handles of the levers may be swung toward each other, when, as shown in Figure 2, wherein I have conventionally illustrated a piston ring in dotted lines at 24, the straight inner edges of the tips 13 will bear against the end edges of the ring so that as the handles are swung, said tips will enter behind the ring, at the ends thereof, for flexing the ends of the ring apart and expanding the ring. The end portions of the ring will thus be flexed out of the ring groove and it is now to be observed that as the handles of the levers are swung toward each other, the arms 14 will be swung forwardly so that the jaws 16 will, in turn, also be swung forwardly. Thus, the flanges 18 of the jaws will be moved to embrace the end portions of the ring, as said end portions emerge from the ring groove so that the ends of the ring will be retained by said jaws against lateral

movement and in alinement with the tips 13 of the prongs 12. Accordingly, the ends of the ring cannot slip out of engagement with said tips and as the movement of the handles toward each other is continued to expand the ring, and the forward movement of the arms 14 is, therefore, also continued, the springs 23 will, as will now be seen, be compressed for tightly pressing the jaws in engagement with the end portions of the ring. Thus the spring pressure on the jaws will be increased with the increase in the expansion of the ring so that as the ring is brought under increased tension by the expansion thereof, to a diameter such that the ring may be slipped over the head of the piston, the jaws will be caused to more firmly engage the end portions of the ring to prevent the ring from springing free of the tool. It will, therefore, be seen that the tool may be readily engaged with the ring, when lying in its ring groove, and operated for expanding the ring so that the ring may be removed with facility over the end of the piston and, of course, the tool may be operated in like manner to apply a ring to the piston with equal facility.

Having thus described invention, what I claim is:

- 30 1. A tool of the character described including coacting levers provided at their forward ends with means to engage the ends of a piston ring whereby the levers may be operated for spreading said ends apart and expanding the ring, means carried by said levers to coact with the end portions of the ring for retaining the ends of the ring engaged by the former means, and means carried by the levers and acting directly on 40 the second-mentioned means for automatically pressing said second mentioned means into engagement with the end portions of the ring as said levers are swung.
- 45 2. A tool of the character described including pivotally connected levers provided at their forward ends with prongs to enter between and engage the ends of a piston ring whereby the levers may be swung for spreading said ends apart and expanding the ring, pivoted jaws carried by said prongs to coact with the ring for retaining

the ends thereof engaged by said prongs, and means for automatically pressing the jaws into engagement with the end portions of the ring as the levers are swung. 55

3. A tool of the character described including pivotally connected levers provided at their forward ends with prongs to enter between and engage the ends of a piston ring whereby the levers may be swung for spreading said ends apart and expanding the ring, jaws pivoted upon the prongs and extending laterally therefrom to coact with the end portions of the ring for retaining the ends thereof engaged by said prongs, 60 arms carried by the levers, and means between said arms and the jaws for pressing the jaws into engagement with the end portions of the ring as the levers are swung. 65

4. A tool of the character described including pivotally connected levers provided at their forward ends with prongs to enter between and engage the ends of a piston ring whereby the levers may be swung for spreading said ends apart and expanding the 70 ring, jaws pivoted upon the prongs and extending laterally therefrom to coact with the end portions of the ring for retaining the ends thereof engaged by said prongs, arms carried by the levers, and means between said arms and the jaws for pressing the jaws into engagement with the end portions of the ring as the levers are swung. 75

5. A tool of the character described including pivotally connected levers provided at their forward ends with prongs to enter between and engage the ends of a piston ring whereby the levers may be swung for spreading said ends apart and expanding the ring, jaws pivoted upon the prongs and provided with flanges to embrace the end portions of the ring for retaining the ends of the ring engaged by said prongs, and means carried by the levers and engaged with the jaws for rocking the jaws into engagement with the ring and applying variable pressure thereto as the levers are swung. 95

In testimony whereof I affix my signature.

WILLIAM F. HIATT. [L. S.] 100
